UNITED STATES PATENT OFFICE.

STERLING H. CAMPBELL, OF ST. LOUIS, MISSOURI.

UNCOUPLING DEVICE FOR RAILWAY-CARS.

1,247,221.

Specification of Letters Patent. Patented Nov. 20, 1917.

Application filed June 27, 1917. Serial No. 177,185.

To all whom it may concern:

Be it known that I, STERLING H. CAMPBELL, a citizen of the United States of America, residing at the city of St. Louis, State 5 of Missouri, United States of America, have invented a certain new and useful Uncoupling Device for Railway-Cars, of which the following is such a full, clear, and exact description as will enable any one skilled in the 10 art to which it appertains to make and use the same, reference being had to the accompanying drawings, forming part of this specification.

My invention relates to an uncoupling device for railway cars, and has for its object the production of a device in which a single link is used to connect the uncoupling lever and the locking pin of the coupler head, and in which the link is provided at its lower 20 end with a head preventing its passage through the eye of the coupler lock. Another object of my invention is to provide forms of brackets for carrying the operating rod.

25 In previous forms of uncoupling devices, as for instance that shown in my prior Patent No. 1,159,470, granted November 9, 1915, the lower end of the link connecting the coupling rod to the locking pin has been provided with an open loop adapted to pass through the eye of the locking pin. In such devices, while the open loop cannot be disengaged from the coupler pin while the parts are in normal position upon the car, 30 this is not apparent to the ordinary railway employees, and I have found in practice that they bend these loops into closed position, thus preventing the removal of the parts in the manner intended. One of the 35 objects of my invention, therefore, is to provide a link in such form that this will not occur.

40 In the accompanying drawings, which illustrate some forms of uncoupling device 45 made in accordance with my invention, Figure 1 is a front elevation; Fig. 2 a top plan view. Fig. 3 an enlarged detail view of my preferred form of link; Fig. 4 an enlarged isometric projection of the inner bracket for 50 carrying the coupling rod; Fig. 5 an enlarged detail view of the outer bracket for carrying the coupling rod; Figs. 6, 7 and 8 modified forms of the brackets; Fig. 9 a modified form of the link shown in Fig. 3;

Fig. 10 a further modification of the link 55 shown in Fig. 3; Fig. 11 an end view; Figs. 12 and 13 a side and edge view respectively of a still further modification of the link; and Figs. 14, 15 and 16 further modifications of the outer bracket for the uncoupling 60 rod.

Like marks of reference refer to similar parts in the several views of the drawings.

10 represents a portion of a railway car, to 65 which my device is applied. 11 is the coupler head provided with the usual knuckle 12, controlled by a locking-pin 13 in which is formed an eye 14, as best shown in Fig. 11. All of these parts may be of any usual and 70 well-known construction.

15 is an operating rod provided at one end with a handle 16 and at the other a forwardly projecting arm 17. The rod 15 is supported in brackets 18, 19 respectively, 75 which will be described in detail hereinafter. Formed on the forward end of the arm 17 is an eye 20 adapted to engage with the upper end of a link 21. This link 21 is provided at its upper end with an over-turned 80 portion 22, and at its lower end with a bend or loop 23, terminating in a head 24, which is made of such size that it cannot pass through the eye 14 of the locking pin 13. Consequently in placing the parts in position 85 the end 22 of the link 21 must be first threaded through the eye 14, and afterward through the eye 20 while the rod is out of normal position, and when the rod is in normal 90 position in the brackets 18, 19, the link 95 cannot become detached. It is evident that the lower end of the link cannot become disengaged from the eye 14, and consequently there will be no apparent reason for closing the loop 23. It will also be evident that the device will not operate if the upper loop is closed, and therefore there will be no inclination on the part of a railway employee to mutilate the device by bending it.

In Fig. 9 I have shown a modified form of 100 link in which the lower loop 23 is made in a different form from that shown in Fig. 3, and the head 24 is replaced by a head 25 formed by bending the metal of the link into a small circle. In this form I prefer to 105 strengthen the loop by upsetting a portion of the metal at 26. In Fig. 10 I have shown a still further modification in which the lower

loop 23 is similar in form to that shown in Fig. 9, but the head 24 is of the same form as shown in Fig. 3. In Figs. 12 and 13 I have shown a still further modification of the 5 link, in which the upper end of the link in place of being formed by a turned over portion, as in Fig. 3, is provided with a spiral loop 27.

The bracket 18 which supports the inner 10 end of the rod 15, is shown in detail in Fig. 4. This bracket consists of a plate 30 adapted to be secured against the front end of the car. Projecting forwardly from this plate 30 is a plate 31. The plate 31 has a 15 portion 32 cut around three sides and bent down so as to form a bearing for the rod 15. The plate 31 is also bent, as shown in Figs. 2 and 4, so that two short arms 33 are formed, which project over the rod 15 and 20 are spaced so far apart laterally that when the rod is turned into a position substantially at right angles to its normal position, the rod may be lifted out of the bracket. The bracket 19 which supports the outer end 25 of the rod 15 is provided with removable means for securing the rod in position. In the forms shown in Figs. 2 and 5 a plate 35 is secured against the end of the car, which plate has forwardly projecting sides 36 30 forming a bearing for the rod, and a plate 37 passing over the top of the rod. Plates 36 and 37 are both provided with openings 38 through which passes a cotter-pin 39, thus removably securing the rod in position. 35 It will be evident that by removing the cotter-pin 39 and swinging the top of the rod through at an angle of substantially 90° it can be lifted from the bracket 19, hereinbefore described. In Figs. 6, 7, 8 14, 15 and 40 16 are shown various modifications of the outer bracket. In each of these the plate 35 is adapted to be secured to the end or some other part of the car, while the plate 36 forms a bearing for the rod. In the forms 45 shown in Figs. 7, 8, 14, 15 and 16 the holes 38 and cotter-pin are arranged so that the cotter pin passes over the rod 15 in place of at one side of it, as in forms shown in Figs. 2, 5 and 6. The action of all, however, 50 is substantially the same. Each provides an elongated bearing for the rod, and has removable means for holding the rod in position. The forms shown in Figs. 14 and 15 are especially adapted to be secured to the 55 end sill of the car. The form shown in Fig. 16 provides a double bearing which may be reversed.

The operation of my device will be clear from the foregoing description. In securing 60 the parts in position, the end 22 of the link is threaded first through the eye 14 of the locking-pin and then through the eye 20 of the rod 15 while the rod is out of position with respect to the brackets. The rod is

then swung around into a position to pass 65 between the two arms 33 of the bracket 18, after which it is swung into a position to engage with the bracket 19, and the cotter-pin 39 placed in position to hold the rod.

Having fully described my invention, what 70 I claim as new and desire to secure by Letters Patent of the United States is:

1. The combination with a railway car, of a coupler head carried thereby, a knuckle-lock for said coupler head provided with an 75 eye, an operating rod, and a link forming a connection between said knuckle lock and operating rod, said link being provided at its lower end with a head incapable of passing through the eye of said knuckle lock.

2. The combination with a railway car, of a coupler head carried thereby, a knuckle-lock for said coupler head provided with an 80 eye, an operating rod, and a link connecting the rod and knuckle lock, said link being 85 provided at its lower end with a head incapable of passing through the eye of said knuckle lock, and the upper end of said link being provided with means forming an operative connection with said rod.

3. The combination with a railway car, of a coupler head carried thereby, a knuckle-lock for said coupler head provided with an eye, an operating rod, and a link connecting the rod and knuckle lock, said link being 95 provided at its lower end with a head incapable of passing through the eye of said lock, the upper end of said link having a flexible connection with said operating rod.

4. The combination with a railway car, of a coupler head carried thereby, a knuckle lock for said coupler head provided with an eye, an operating rod also provided with an eye, and a link connecting said knuckle lock and operating rod, said link being provided at its lower end with a head to prevent its passage through the eye of said knuckle lock, whereby to place said link in operative position it must be first threaded through the eye of said knuckle lock and then through 110 the eye of said operating rod.

5. The combination with a railway car, of a coupler head carried thereby, a knuckle lock for said coupler head provided with an eye, an operating rod also provided with an 115 eye, and a link connecting said knuckle lock and operating rod, said link being provided at each end with a looped portion, the lower end of said link being provided with a head to prevent its passage through the eye of the knuckle lock, whereby the upper end of said link must be threaded through said eyes to bring the loop at its lower end into engagement with the eye of the knuckle lock.

6. The combination of a railway car, of a 125 coupler head carried thereby, a knuckle lock for said coupler head provided with an eye, an operating rod also provided with an

eye, a single link connecting said knuckle lock and operating rod by engaging with their eyes, the upper end of said link being provided with an open loop, and the lower end being provided with a head incapable of passing through the eye of the knuckle lock, whereby disengagement of the link

from the knuckle lock is prevented without first disengaging the link from the operating rod.

10

In testimony whereof, I have hereunto set my hand and affixed my seal.

STERLING H. CAMPBELL, [L.S.]
